UNITED STATES PATENT OFFICE

JENS BRODERSEN HIORTH, OF HOVIK, NEAR OSLO, NORWAY

GUIDE APPARATUS FOR THE PROPELLER STREAM OF VESSELS

Application filed January 3, 1929, Serial No. 330,034, and in Germany January 7, 1928.

It is necessary in order to obtain the best possible efficiency of a ship's propeller to adapt the propeller to the lines of the ship, in other words to design the propeller with 5 due consideration to the suction of the propeller peculiar to each individual ship and to the wake of the ship. With this end in view the use of so-called wake propellers has been suggested in which the varying wake 10 conditions in the different spheres of action of the propeller have been taken into consideration.

The object of the present invention is to 15 form the guide apparatus for the propeller stream, arranged forward of and/or behind the propeller, due consideration being given suction and wake conditions respectively in such a way that improved efficiency of propulsion will be obtained.

20 In prior guide apparatus constructions the vanes, regardless of whether they were arranged vertically, horizontally or inclined, always have been carried out with constant maximum thickness or with a maximum 25 thickness decreasing outwardly from the propeller axis.

According to the present invention the 30 guide apparatus, with due consideration to the suction of the propeller and to the wake, is so constructed that the sections of the vanes are comparatively thin in the sphere nearest to the propeller axis and gradually increase in thickness outwards. The sections, in other 35 respects, may be shaped differently as in usual guide apparatus, symmetrically or asymmetrically, with straight or curved centre line, plane, convex or concave pressure surface, wing shaped or with other shapes adapted to meet the particular conditions in each 40 case.

The guide apparatus may be attached to 45 the hull of the vessel or to the rudder post, or to the rudder turnable with the same. Also the rudder body itself, especially balanced rudders, may be formed as a guide apparatus with more narrow sections near the propeller axis and increasing sections upwards and downwards.

50 In the accompanying drawing: Fig. 1 is

an elevational view of an embodiment of my invention;

Fig. 2 shows sections through the vertical 55 guide vanes taken on the lines I—I, II—II and III—III of Fig. 1; and

Fig. 3 shows sections of the horizontal 60 guide vanes taken on the lines IV—IV, V—V and VI—VI of Fig. 1.

Referring to the drawings in detail, 65 1 designates the propeller and 2 a rudder post to which vertical guide vanes 3 and horizontal guide vanes 4 are attached. These guiding vanes, as clearly indicated in the sectional views of Fig. 2 and Fig. 3, are of minimum thickness near the axis of the propeller 1 and gradually increase in thickness to a point near the outer end or tip of the vane.

Having now particularly described and ascertained the nature of my said invention and in what manner the same is to be performed, 70 I declare that what I claim is:

Guide apparatus for the propeller stream of vessels, in which the sections of the guide vanes are of minimum thickness near the propeller axis and increase in thickness outwardly from the propeller axis to a point 75 near the outer end or tip of the vane.
